UNITED STATES PATENT OFFICE.

FREDRICK A. ROBERTS, OF DICKEY, NORTH DAKOTA.

LINE-SHAFT JOURNAL-BOX.

1,152,550.

Specification of Letters Patent.

Patented Sept. 7, 1915.

Application filed September 25, 1912. Serial No. 722,354.

To all whom it may concern:

Be it known that I, FREDRICK A. ROBERTS, citizen of the United States, residing at Dickey, in the county of Lamoure and State of North Dakota, have invented certain new and useful Improvements in Line-Shaft Journal-Boxes, of which the following is a specification.

This invention relates to journal boxes and has as its primary aim to provide a journal box particularly well adapted for use in connection with line-shafts.

A further aim of the invention is to provide a line-shaft journal box which may be readily assembled with the shaft to be journaled, without the necessity of dismounting the shaft.

For a full understanding of the invention reference is to be had to the following description and accompanying drawing, in which:—

Figure 1 is a top plan view of the journal box embodying the present invention, the cap of the box being removed. Fig. 2 is a vertical longitudinal sectional view on the line 2—2 of Fig. 1.

Corresponding and like parts are referred to in the following description and indicated in all the views of the drawing by the same reference characters.

In the drawings the box is illustrated as including a bottom 1, side walls 2, end-walls 3, and a cap or cover 4. The end-walls 3 are formed with recesses 5 which open at their upper edges, the bottom walls of these recesses being semi-cylindrical whereby to conform to the cross-sectional contour of the shaft to be journaled. The cap-plate 4 is formed or provided at its ends with depending fillers 6 which fit within the recesses 5 and these fillers at their lower ends are cut away as at 7 so as to conform to the cross-sectional contour of the upper side of the shaft. The opposite side walls 2 of the box are formed with vertically extending oppositely located grooves 8 in which are fitted the vertical edges of the division-plates 9. By referring to the drawings, it will be observed that each of these division-plates is located in a plane parallel to and adjacent an end-wall 3 of the box. The division-plates 9 are recessed as at 10 in the same manner as are the end-walls of the box and they form, in conjunction with the said end-walls and the adjacent portions of the side walls, compartments in

which the lubricant is contained. Arranged within the box between the division-plates 9 is a pillow-block 11 having its upper side channeled as at 12 to receive the lower side of the shaft to be journaled. A cap-plate 13 is disposed upon the pillow block and is formed in its under side with a channel 14 fitting the upper side of the said shaft, the shaft being indicated by the numeral 15. The cap-plate 13 is secured in place by means of suitable stud-bolts 16 which are fitted through the plate, through packing strips 17 arranged between the under side of the plate and the upper side of the pillow-block, and threaded into the said pillow-block.

For the purpose of preventing leakage of lubricant through the openings in the end walls of the pockets, packing devices are provided which, however, form no part of the present invention.

Having thus described the invention what is claimed as new is:—

1. A journal box including a body casing having end walls provided with shaft receiving openings, a pillow block formed integrally with the bottom wall of the body casing and arranged intermediate the length thereof, said pillow block being provided in its upper face with a longitudinally extending shaft receiving channel, a half bearing plate, means for securing the half bearing plate on the upper face of the pillow block, a pair of removable partition walls arranged transversely in the body casing and supported by the bottom wall thereof, said partition walls bearing against the terminals of the pillow block and a removable cover plate for the body casing.

2. In a journal box having opposite walls provided with journal receiving openings, a pillow block rising from the bottom wall of the box and having a longitudinal extending journal receiving channel formed in its upper face, a half bearing plate removably secured upon the pillow block and arranged to hold a journal against displacement from the pillow block and a pair of transversely extending partition walls supported by the bottom wall of the box and arranged one at each end of the pillow block, said walls forming in connection with the adjacent end walls of the box lubricant receiving compartments.

3. A journal box including a body casing having opposite walls provided with shaft

receiving recesses opening through the upper edges thereof, a pillow block rising from the bottom wall of the body casing and having a longitudinally extending journal receiving channel formed in its upper face, transversely arranged partition walls supported by the bottom wall of the body casing at the longitudinal extremities of the pillow block, said partition walls having 10 shaft receiving recesses formed therein opening through the upper edges thereof and disposed to receive a journal seating in the channel formed in the pillow block, and a cap plate bearing over the journal and operatively connecting the journal with the pillow block.

4. A journal box including a body casing having a cap plate removably connected thereto and being provided with recesses in 20 opposite walls thereof opening through the free edges of said walls adjacent said cap plate, said recesses being disposed to receive a journal, a pillow block rising from the bottom wall of the body casing and disposed 25 to operatively support the journal, transversely arranged partition walls supported by the bottom wall of the body casing, said partition walls having recesses formed therein opening through their upper edges and

disposed to receive the journal, and fillers 30 carried by the cap plate and normally fitting within the recesses formed in the opposite walls of the body casing to bear over the adjacent side of the journal.

5. A journal box including a body casing 35 having recesses formed in opposite walls thereof opening through the upper edges of said walls and disposed to removably receive a journal, a pillow block rising from the bottom wall of the body casing and disposed to operatively support the journal, 40 vertically extending grooves formed in opposite walls of the body casing intermediate the length of the journal within the casing, transversely arranged partition walls 45 removably fitted within said grooves and supported by the bottom wall of the body casing, said partition walls having recesses formed therein opening through their upper edges and disposed to removably receive 50 the journal, and a cap plate detachably connecting the journal with the pillow block.

In testimony whereof I affix my signature in presence of two witnesses.
